James Stevenson,
By their attorney,
Edward P. Thompson.

UNITED STATES PATENT OFFICE.

WILLIAM LIVINGSTONE AND JAMES STEVENSON, OF BELFAST, IRELAND.

APPARATUS FOR BALANCING, RAISING, OR LOWERING CARRIAGE OR OTHER WINDOWS.

SPECIFICATION forming part of Letters Patent No. 792,602, dated June 20, 1905.

Application filed September 27, 1904. Serial No. 226,152.

To all whom it may concern:

Be it known that we, WILLIAM LIVINGSTONE, secretary, and JAMES STEVENSON, engineer, subjects of the King of Great Britain, residing at Belfast, in the county of Antrim, Ireland, have invented certain new and useful Improvements in Apparatus for Balancing, Raising, or Lowering Carriage or other Windows, (for which application has been made in Great Britain, No. 9,005, dated April 19, 1904,) of which the following is a specification.

This invention has for its object mechanism connected with the windows of carriages, steamers, and the like whereby the window can be raised and lowered with the greatest ease, while it is not possible for the passengers or others to tamper with the mechanism except by dismantling the carriage - door or other structures to which the window is fixed.

The invention will now be described with reference to the accompanying drawings, in which the invention is shown as applied to the window in the door of a railway-carriage, Figure 1 being an elevation of such a door, Fig. 2 an enlarged vertical section, Fig. 3 an enlarged sectional plan, and Fig. 4 a detail view of the handle.

In carrying out the invention the window-frame *a* is attached at two points *b* intermediate between the sides of the door or window box *c* to two endless bands or chains *d*, between which a balance - weight *e* of equal weight to the window is fixed. The balance-weight *e* and window *a* are so attached to the bands *d* that when the lower edge of the window, which is attached to the bands *d*, is at the lowest point the balance-weight is at the highest point, and vice versa. The two bands *d* pass over pulleys or the like *f*, arranged on a rod or spindle *g* near the bottom of the door-frame or window-box *c*, into which the window-frame *a* falls. The two bands *d* also pass over similar pulleys *h* on a spindle or shaft *k* near the top of the said window-box or solid portion of the door-frame. On this upper shaft or spindle *k* a bevel-wheel *l* is arranged, acting on a second bevel-wheel *m*, located inside the door or window box *c* nearer the interior of the carriage. On this second

bevel-wheel *m* or on its spindle *n* a sprocket-wheel *o* is arranged, while a second sprocket-wheel *p*, also on a spindle, is arranged close to the other end of the upper spindle or shaft *k*. A sprocket chain or band *q* passes round these two sprocket-wheels *o* and *p*, while a suitable handle *r* is secured to an enlarged link *s* in the chain *q*. This handle *r* passes through a long slot *t* in the covering of the door-frame or window-box and is so arranged as to be capable of being fixed in any position along the slot *t*. The arrangement found most preferable for this object is shown in detail in Fig. 4. The handle *r* is mounted on a small screwed shaft *u*, which engages in the enlarged link *s*, hereinbefore referred to. The handle *r* takes over the screwed part of this small shaft *u*, so that on being turned it will approach the frame of the door or window box and be clamped against the same. The small shaft *u* is provided with a guide-piece *v*, adapted to slide along just inside the door or window box frame and over a bar *x*, so as to give a purchase for the handle *r* when it is desired to lock the same in position, the provision of the bar *x* having the advantage of preventing people from getting their fingers into the mechanism.

The mode of action is as follows: When the window *a* is open, nothing need appear to view except perhaps the very top of the window, on which a finger-ledge *w* may be arranged, and the slot *t* and the handle *r* projecting through it, the handle then being at one end, as shown in Fig. 1, and close to the sprocket-wheel *o*. Should the occupant of the carriage wish to partially close the window, he slightly unscrews the handle *r* and pushes or pulls the same sidewise and the window-frame at once rises to a proportionate height where it can be clamped in position by screwing up the handle *r*. If it is desired to entirely close the window, the handle is pushed right to the opposite end of the slot *t* and then screwed up again. To open the window, the reverse action is gone through.

It will of course be obvious that instead of the two bands *d* a single band might be used; but this device would not work smoothly 100

and would not be so good from a constructional point of view. It will also be obvious that the arrangement might be adopted equally well for a window descending from a box above, in which case the parts would simply be reversed.

The invention is applicable not merely for windows, but for shutters, panels, strong blinds, and other articles required to be raised or lowered, while a different device than that shown for clamping the window in position might be used, such as a ratchet or a hinged handle arranged to take over stops along the slot *t*.

15 We declare that what we claim is—

1. In a mechanism for raising and lowering windows in which the horizontal movement of the handle causes the vertical movement of the window, a window-box, a slot in said box, a screwed spindle projecting from said slot, and a handle provided with an internal thread adapted to screw on said spindle and so be clamped against said window-box.

25 2. In a mechanism for raising and lowering windows, a window-box to receive the window, a handle capable of horizontal movement, means intermediate the handle and the window whereby the horizontal movement of the handle is converted into a vertical movement of the window, a slotted part, a bar over which the slotted part takes, and a shaft on said slotted part on which shaft said handle is adapted to screw.

35 3. In a mechanism for raising and lowering windows, a window-box, a handle extending to the exterior of said window-box, vertical bands secured to the window, means for operating said vertical bands on the horizontal movement of said handle, guiding means for said handle interior of said box, and means for clamping said handle in position on turning the same, substantially as described.

45 4. In a mechanism for raising and lowering windows, a window-box, a handle extending to the exterior of said window-box, a horizontal slot to allow of the movement of said handle, guiding means interior of said box for said handle, screw means intermediate said handle and said guiding means, vertical bands secured to the window, bevel-gearing actuated by the horizontal movement of said handle, and means for actuating the said vertical bands by the bevel-gearing, substantially as described.

55 5. In a mechanism for raising and lowering windows, a window-box, a bar interior of said box, a handle extending to the exterior of said window-box and guided by said bar, screw means intermediate said bar and said handle, vertical bands secured to said window, shafts carrying said bands, gearing actuating one of said shafts, and sprocket-wheels and a sprocket-chain connected to

said bevel-gear and operated by said handle, substantially as described.

6. In a mechanism for raising and lowering windows, a window-box, a handle extending to the exterior of said box, vertical bands secured to said window, shafts carrying said bands, bevel-gearing actuating one of said shafts, sprocket-wheels and a sprocket-chain connected to said bevel-gear and operated by said handle, and means for screwing up said handle against the window-box in any desired position, substantially as described.

7. In a mechanism for raising and lowering windows, a window-box for receiving the window when open, a handle capable of horizontal movement in a slot in said box, a bar in said box, a slotted part on said handle taking over said bar, a sprocket-chain secured to said handle inside the box, sprocket-wheels carrying said chain, means connected to said sprocket-wheels for raising and lowering the window on the handle being operated, and means for screwing said handle up against the window-box.

8. In a mechanism for raising and lowering windows, a window-box, bevel-gearing, bands actuated by said gearing, said bands being secured to the window, a handle, means for actuating said bevel-gearing by said handle, a slot in the window-box for guiding said handle, a guiding-piece integral with a screw-threaded part, said handle taking over said threaded part, and a bar in said box over which said guiding-piece takes, substantially as described.

9. In a mechanism for raising and lowering windows, a window-box having a horizontal slot therein, vertical bands secured to the window, pulleys carrying said bands, shafts upon which said pulleys are fixed, bevel-gearing for actuating one of said shafts, sprocket-wheels one of which is connected to said bevel-gearing, a sprocket-chain carried by said sprocket-wheels, a projecting piece attached to said chain and extending to the exterior of said box through said slot, and a screw-knob for adjusting and clamping said piece to said box at any desired position along said slot.

10. In a mechanism for raising and lowering windows, a window-box, a slot in said box, actuating means for said mechanism adapted to be moved along said slot, said means comprising a short shaft, a handle adapted to screw on said shaft, a bar in said box, and a slotted piece on said shaft taking over said bar, whereby the actuating means can be clamped in any desired position.

11. In a mechanism for raising and lowering windows, a window-box to receive the window when open, a counterweight, endless bands, said window and said counterweight being carried by said bands, shafts supporting said bands, sprocket-wheels and a sprocket-

chain, bevel - gear intermediate said shafts and one of said wheels, means for actuating said chain, said means comprising a short shaft, a handle adapted to screw on said shaft, a bar in said box, and a slotted piece on said shaft taking over said bar, whereby the window can be actuated and clamped in any desired position.

12. In a mechanism for raising and lowering windows, a window-box for receiving the window when open, a horizontal shaft near the top of said box, a second horizontal shaft near the bottom of the same, pulleys on said shafts, endless bands passing over said pulleys and secured to near the bottom of said window, a counterweight secured to said bands on the side of the pulleys remote from the window, a bevel-wheel on the upper of the two shafts, a horizontal bar near the 20 level of said upper shaft, a further bevel-wheel bearing in said bar and gearing with the first bevel-wheel, sprocket-wheels, one

rigidly secured to said second bevel-wheel and the other mounted on said bar at the opposite end of the window-box, a sprocket-chain over said sprocket-wheels, a slot in said window-box, a small shaft passing through said slot and secured at one end to said sprocket-chain, a handle taking over and screwing on the other end of said small shaft 25 outside the window-box, a bar interior of the window-box opposite the said slot, and a guide-piece on said small shaft taking over said last-named bar, substantially as described.

In witness whereof we have hereunto signed our names, this 15th day of September, 1904, in the presence of two subscribing witnesses.

WILLIAM LIVINGSTONE.
JAMES STEVENSON.
